UNITED STATES PATENT OFFICE.

MANFRED U. LOREE, OF MIAMISBURG, ASSIGNOR TO THE NATIONAL CASH REGISTER COMPANY, OF DAYTON, OHIO.

CASH INDICATOR AND REGISTER.

SPECIFICATION forming part of Letters Patent No. 404,045, dated May 28, 1889.

Application filed March 16, 1888. Serial No. 267,305. (No model.)

To all whom it may concern:

Be it known that I, MANFRED U. LOREE, a citizen of the United States, residing at Mi-
5 amisburg, in the county of Montgomery and
State of Ohio, have invented certain new and
useful Improvements in Cash Registers and
Indicators, of which the following is a full,
clear, and exact description, reference being
had to the accompanying drawings, forming
10 part of this specification.

My invention relates to that class of cash
registers and indicators in which the opera-
tion of any one of a series of keys exposes to
view a numbered tablet corresponding in
15 value to that of the key operated, and simul-
taneously sounds a gong and registers the
amount upon the mechanism within the
case.

It has for its object the improvement in the
20 construction of this class of machines, and its
novelty will be herein set forth, and dis-
tinctly pointed out in the claims.

In the accompanying drawings, Figure 1,
Sheet 1, is a plan view of my improved ma-
chine removed from its case. Fig. 2, Sheet 2,
25 is a sectional side elevation of the same
through the dotted line $\alpha\alpha$ of Fig. 1. Fig. 3,
Sheet 2, is an enlarged sectional detail of the
traveling pointer. Fig. 4, Sheet 3, is a sec-
30 tional detail plan view through the dotted
line yy of Fig. 2. Fig. 5, Sheet 2, represents
a detail to be referred to hereinafter.

The same letters of reference are used to
indicate identical parts in all the figures.
35 The machine is supported within a locked
case or cabinet, (indicated by the dotted lines
in Fig. 2,) which may be of the usual or any
suitable construction, with glass - covered
40 openings at its top, through which the tab-
lets are exposed to view when the keys are
operated.

The frame of the machine is composed of the
two upright sides A and front and rear cross
guide-bars, B C, in which the horizontal and
45 parallel keys or pull-bars D are supported
and guided. These keys project from the
front of the case, and at that point are pro-
vided with or formed into finger-loops a, and
carry buttons b, with numbers indicating
50 their values. Any suitable stops, c, limit the
play of the keys forward and backward. I

have shown in the present instance twenty
keys, in value from five cents up to one dol-
lar in multiples of five, and beginning at the
right. As seen in Figs. 2 and 4, each key is 55
provided with a coiled resetting - spring, d,
fastened at one end to the bar C and at the
other to the key, so that after a key has been
drawn out and released its spring d will re-
tract and reset it. 60

Strung upon a shaft, E, supported by the
sides A at the back of the machine, is a se-
ries of bell-crank, F, one for each key, and
whose lower vertical arms engage with pro-
jections e upon the rear ends of the keys. 65

The usual vertical tablet-rods, G, are sup-
ported in suitable guides, H, and provided
with the usual numbered tablets, I, and de-
tents or supporting-shoulders f, which press
forward and are caught upon the usual vi-
brating wing, J, journaled in the frame-work,
70 to hold the tablet-rod with its tablet exposed
to view whenever its corresponding key is
operated. The rod of the five-cent tablet
rests upon the horizontal arm of the bell-crank 75 F which is engaged by the five-cent key, the
rod of the ten-cent tablet on the arm of the
bell-crank which is engaged by the ten-cent
key, and so on throughout the series.

It results from the construction that when-
ever any key is drawn out its bell-crank will
be vibrated and the tablet-rod carried thereby
will be raised until its shoulder f has passed
the wing, as seen by the dotted lines in Fig. 2.
Upon the release of the key it will be reset, 85
together with its bell-crank, while the tablet-
rod, by means of its shoulder resting on the
wing, will be held up with its tablet exposed
to view through the reading-opening. The
tablet will remain exposed until another key 90
is operated to expose another tablet, where-
upon the vibration of the wing by the pas-
sage of the shoulder on the second tablet-rod
will disengage the first and permit its rod and
tablet to drop. Auxiliary means may be em- 95
ployed, as presently explained, to vibrate the
wing in connection with or independent of
the shoulders upon the tablet-rods.

To sound the gong K whenever any key is
drawn out, I place a bar, L, across all of the 100
keys in front of the pins connecting the springs
d to the keys. This bar is pivoted at one end,

as at *g*, Fig. 4, and is held back against a pin or other stop, *h*, by any suitable spring, *i*. The gong-hammer *M* is pivoted, as at *j*, and has its lower end connected by a link, *k*, to the vibrating end of the bar *L*. This bar *L* is so adjusted and inclined with reference to the pins on the keys that it is vibrated to the same extent by each key. It will be seen from this that whenever any key is drawn out to expose a tablet the bar *L* will be drawn forward by the pin on said key and the gong will be struck. Upon the release of the key the spring *i* will reset the bar.

Where auxiliary means are employed to vibrate the wing they may consist of the arm *N*, Fig. 2, pivoted at its upper end, as at *l*, and at its lower end to the link *k*, as at *m*, and carrying a pivoted dog, *n*, whose shouldered nose overlaps and engages with the wing. It will then be seen that the vibration of the bar *L*, when the key is operated, draws forward the arm *N* and vibrates the wing until the shoulder of the dog overrides the edge of the wing and releases the same, which then falls back to its normal position by gravity, or may be aided by any suitable spring.

The remaining feature of the machine is the registering mechanism, which may be described as follows:

At one side of the machine is a registering-wheel, *P*, provided on its periphery with a ratchet containing in this instance one hundred teeth. The periphery of this wheel is further equally divided off into one hundred numbers from 0 to 4.95 in multiples of five. A stationary reading-plate, *o*, may be secured to the frame of the machine at any suitable point where the reading is to be taken from the periphery of the wheel. A vibrating pawl-carrier, *Q*, is loosely hung concentric with the axis of the wheel by the side of the same, and has pivoted to its upper end a spring-pawl, *p*, provided with a lateral extension engaging with the teeth of the ratchet on the wheel *P*, as seen in Fig. 5. The lower end of the pawl-carrier is connected by a link, *S*, with the free end of a horizontally-vibrating bar, *T*, extending across the tops of all of the keys and suitably pivoted, as at *q*, to the opposite side of the frame-work. This bar *T* is normally held by a spring, *r*, against any suitable stop, *s*, which limits its backward play, in which position the pawl-carrier is inclined forward at its upper end, as seen in Fig. 2. Each key is provided with a pin or projection, *t*, arranged to engage with the bar *T* whenever the key is operated. Whenever the pawl-carrier is actuated through the medium of the bar *T*, its pawl will travel backward over the ratchet of the wheel *P* and engage with the proper tooth thereof, the wheel and ratchet in the meantime being held stationary by the dog *U*. Upon the release of the operated key the spring *r* resets the bar *T*, thereby throwing forward the upper end of the pawl-carrier and causing its pawl to turn the wheel *P*. The distances of the pins

t from the bar *T* are so adjusted that the key of lowest value—in this instance the five-cent key—will vibrate the bar *T* just sufficiently to cause the pawl-carrier and its pawl to turn the wheel *P* one notch when the key has been drawn out to its farthest extent and released, as will be readily understood. The operation of the key of the next higher value—in this instance the ten-cent key—will cause the wheel *P* to be turned two notches, and so on up to the key of highest value—in this instance the one-dollar key—whose operation will cause the wheel *P* to be turned twenty notches.

To prevent the wheel *P* from turning too far forward under the impetus of its actuation, I employ a stop—in this instance a lug, *V*, with an inclined lower face—so adjusted and applied to the frame that the projecting end of the pawl is caught under it and locked in its notch in the ratchet, thereby positively stopping and locking the wheel *P* at the exact point of the completion of the stroke of the pawl, as will be readily understood.

While I have shown the bar *T* as arranged diagonally across the keys, so that its free end vibrates both forward and back of a line through its pivot at right angles to the keys, it will be understood that this arrangement is merely a convenient mode of adjustment and that said bar may extend across said keys at right angles to them and have its vibration entirely forward of the line through its pivotal point, in which event the adjustment of the pins on the keys would be varied accordingly. It is also obvious that the resetting-spring *r* for the bar *T*, instead of being applied directly to the bar, as shown, might be applied to the pawl-carrier for the same purpose, or a weight and cord might be substituted for it.

As a supplemental mechanism for receiving the amounts registered by the revolutions of the wheel *P*, I provide the following: A screw-shaft, *O*, suitably journaled in the frame of the machine, extends transversely above the keys, as shown, and at one end is rigidly secured to the wheel *P*, with their axes concentric with each other. In the present instance this shaft extends through the wheel *P*, and forms the support for the same, as well as the pivotal support for the vibrating pawl-carrier *Q*, which is loosely hung thereon.

Upon the screw-shaft *O* and engaging with its thread is a traveling pointer, *W*, which rests and slides upon a fixed registering-bar *u*. This registering-bar *u* is divided into spaces corresponding to the pitch of the screw, so that each complete revolution of the screw and wheel *P* will move the pointer just one space on the registering-bar *u*. As one complete revolution of the wheel *P* in this instance registers five dollars, each space on the bar *u* will indicate five dollars.

In starting the machine—for instance, at the commencement of a day's business—the

pointer would be at the extreme right of the screw-shaft next to the pawl-carrier and pointing at 0. The wheel P would likewise show 0 at its reading-point o. Upon now operating the machine a number of times the wheel P will register the total amount until the latter has reached five dollars, whereupon the pointer W will have been moved one space on the bar u and will point to the \$5 mark on said bar, and the wheel P will exhibit 0 at the reading-point o. Upon continuing the operation of the machine until the pointer W reaches the position shown in Fig. 1 a total registry of seventy-five dollars and seventy-five cents will be indicated, the seventy-five dollars being indicated on the bar u and the remainder of the amount on the wheel P at the reading-point o. It will be understood that the amount registered on the bar u is always indicated by the division-mark at which the pointer W is pointing or has just passed, and that the remainder of the amount registered, which may be any amount from five cents to four dollars and ninety-five cents, is taken from the wheel P at the point o. Thus, if the pointer W rests at any point of the space between the \$75 and \$80 marks, as shown, for instance, in Fig. 1, the amount to be read from the bar u is only seventy-five dollars and the balance is to be read from the wheel P at the point o.

The body of the pointer W may be an ordinary nut; but in order to readily reset the pointer to 0, as at the end of a day's business, without the necessity of turning the shaft O backward, I have not made it a nut, but have constructed it with a spring-catch, v, Fig. 3, which is held in a slot in the pointer and has its lower edge so shaped as to fit into and engage with the thread of the screw, and serves as the means by which the pointer is made to travel as the screw is rotated. By lifting this catch the pointer may slide freely upon the screw, and thus be reset to 0 without delay or trouble and be again re-engaged with the screw by releasing the catch.

As is usual in this class of machines, the adjustment of the parts is such that the gong-hammer will strike the gong and the projection on the tablet-rod of the operated key pass and be caught by the supporting-wing at the exact moment the key has reached its extreme limit of operation, so that it is impossible to so operate a key as to sound the gong and expose its corresponding tablet without registering the full value of such key.

Where it is desired that the machine shall have a number of keys indicating multiples of one dollar as well as cent-keys, the screw-shaft O and wheel P may be duplicated with the set of dollar-keys operating the one and the set of cent-keys the other, as will be readily understood. In such instance the dollar-registering wheel may be located on the left hand of the machine and its screw-shaft extend from left to right across or partially across the machine, and be provided with a

registering-bar and pointer similar to those of the cent-registering wheel. A separate arm, T, arranged to be actuated by pins on the dollar-keys and connected to a pawl-carrier to operate the dollar-registering wheel would be provided in a similar manner to that for the cent-keys and their registering-wheel.

It will be understood that those features of my invention above described which relate to the stop that engages with the pawl to lock the registering-wheel at the completion of the stroke of the pawl and the screw-shaft provided with its pointer and registering-bar and combined with the registering-wheel are applicable to various forms of cash-registers other than the one described and shown in this application.

Having thus fully described my invention, I claim—

1. In a cash register and indicator, the combination, with a series of horizontally-reciprocating keys of fixed values, of a series of vertically-reciprocating tablet-rods carrying indicating-tablets and a series of bell-cranks actuated by said keys and engaging with said tablet-rods, whereby upon operating any one of said keys its corresponding tablet-rod is elevated to expose its tablet to view, substantially as described.

2. In a cash register and indicator, the combination of a series of horizontally-reciprocating keys of fixed values, a series of vertically-reciprocating tablet-rods provided with projections and carrying indicating-tablets, a supporting-wing, and a series of bell-cranks actuated by said keys and engaging with the tablet-rods, whereby upon operating any one of said keys its corresponding tablet-rod is elevated and its tablet held exposed to view, substantially as described.

3. In a cash register and indicator, the combination of a series of horizontally-reciprocating keys of fixed values, a series of bell-cranks pivoted on a horizontal shaft at the rear of the machine, with their vertical arms engaging with the rear ends of the keys, a series of vertically-reciprocating tablet-rods provided with projections and resting at their lower ends on the horizontal arms of said bell-cranks and carrying at their upper ends indicating-tablets, and a supporting-wing, whereby upon operating any one of said keys its corresponding tablet-rod is elevated and its tablet held exposed to view, substantially as described.

4. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, and a pawl actuated by said bar and engaging with the ratchet on the registering-wheel, whereby upon operating

any one of said keys its value is registered on said registering-wheel, substantially as described.

5. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, and a pawl carried by said carrier and engaging with the ratchet on the registering-wheel, whereby upon operating any one of said keys its value is registered on said registering-wheel, substantially as described.

10. 6. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, and a stop arranged to engage with said pawl to positively lock the registering-wheel at the completion of the stroke of said pawl, substantially as described.

15. 7. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, and a stop arranged to engage with said pawl to positively lock the registering-wheel at the completion of the stroke of said pawl, substantially as described.

20. 8. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, and a stop arranged to engage with said pawl to positively lock the registering-wheel at the completion of the stroke of said pawl, substantially as described.

25. 9. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, and a stop arranged to engage with said pawl to positively lock the registering-wheel at the completion of the stroke of said pawl, substantially as described.

30. 10. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, and a stop arranged to engage with said pawl to positively lock the registering-wheel at the completion of the stroke of said pawl, substantially as described.

7. In a cash register and indicator, the combination, with a series of horizontally-reciprocating keys of fixed values and a registering-wheel provided with a ratchet, of a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, a pawl carried by said carrier and engaging with the ratchet on the registering-wheel, and a stop arranged to engage with said pawl to positively lock the registering-wheel at the completion of the stroke of said pawl, substantially as described.

50 8. In a cash register and indicator, the combination of a series of horizontally-reciprocating keys of fixed values, a registering-wheel provided with a ratchet, a horizontally-vibrating bar extending transversely across said keys, a resetting-spring for said bar, a series of projections on said keys at varying distances from said bar and arranged to engage therewith, a pawl actuated by said bar and engaging with the ratchet on the registering-wheel, a horizontal screw-shaft secured to the axis of the registering-wheel and revolving therewith, a pointer on said shaft and engaging with the thread thereof, and a registering-bar along which said pointer travels, substantially as and for the purpose described.

9. In a cash register and indicator, the combination of a series of horizontally-reciprocat-

ing keys of fixed values, a registering-wheel provided with a ratchet, a horizontally-vibrating bar pivoted at one side of the keys and extending transversely across the same, a series of projections on said keys arranged to engage said bar and vibrate it to different degrees, a pawl actuated by said bar and engaging with the ratchet of the registering-wheel, a horizontal screw-shaft secured to the axis of the registering-wheel and revolving therewith, a pointer on said shaft and engaging with the thread thereof, and a registering-bar along which said pointer travels, substantially as and for the purpose set forth. 70 75 80

10. In a cash register and indicator, the combination of a series of horizontally-reciprocating keys of fixed values, a registering-wheel provided with a ratchet, a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said vibrating bar, a pawl carried by said carrier and engaging with the ratchet on the registering-wheel, a horizontal screw-shaft secured to the axis of the registering-wheel and revolving therewith, a pointer on said shaft and engaging with the thread thereof, and a registering-bar along which said pointer travels, substantially as and for the purpose described. 85 90 95 100

11. In a cash register and indicator, the combination of a series of horizontally-reciprocating keys of fixed values, a series of tablet-rods and indicating-tablets operated thereby, a registering-wheel provided with a ratchet, 105 a horizontally-vibrating bar extending transversely across said keys, a resetting-spring for said bar, a series of projections on said keys at varying distances from said bar and arranged to engage therewith, and a pawl 110 actuated by said bar and engaging with the ratchet on the registering-wheel, whereby upon operating any one of said keys its corresponding tablet is exposed to view and its value registered on said registering-wheel, 115 substantially as described.

12. In a cash register and indicator, the combination of a series of horizontally-reciprocating keys of fixed values, a series of vertically-reciprocating tablet- rods operated thereby and provided with projections and carrying indicating-tablets, a supporting-wing, a registering-wheel provided with a ratchet, a horizontally-vibrating bar extending transversely across said keys, a resetting-spring for said bar, a series of projections on said keys at varying distances from said bar and arranged to engage therewith, and a pawl actuated by said bar and engaging with the ratchet on the registering- wheel, whereby upon operating any key its value is registered on the registering-wheel and its corresponding tablet-rod is elevated and its tablet held exposed to view, substantially as described. 120 125 130

13. In a cash register and indicator, the combination of a series of horizontally-reciprocating keys of fixed values, a series of vertically-reciprocating tablet-rods carrying indicating-tablets, a series of bell-cranks actuated by said keys and engaging with said tablet-rods, a registering-wheel provided with a ratchet, a horizontally-vibrating bar extending transversely across said keys, a resetting-spring for said bar, a series of projections on said keys at varying distances from said bar and arranged to engage therewith, and a pawl actuated by said bar and engaging with the ratchet on the registering-wheel, whereby upon operating any key its corresponding tablet is exposed to view and its value registered on the registering-wheel, substantially as described.

14. In a cash register and indicator, the combination of a series of horizontally-reciprocating keys of fixed values, a series of bell-cranks pivoted on a horizontal shaft at the rear of the machine with their vertical arms engaging with the rear ends of the keys, a series of vertically-reciprocating tablet-rods provided with projections and resting at their lower ends on the horizontal arms of said bell-cranks and carrying at their upper ends indicating-tablets, a supporting-wing, a registering-wheel provided with a ratchet, a horizontally-vibrating bar extending transversely across said keys, a resetting-spring for said bar, a series of projections on said keys at varying distances from said bar and arranged to engage therewith, and a pawl actuated by said bar and engaging with the ratchet on the registering-wheel, whereby upon operating any key its value is registered on the registering-wheel and its corresponding tablet-rod is elevated and its tablet held exposed to view, substantially as described.

15. In a cash register and indicator, the combination of a series of horizontally-reciprocating keys of fixed values, a series of tablet-rods and indicating-tablets operated thereby, a registering-wheel provided with a ratchet, a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, and a pawl carried by said carrier and engaging with the ratchet on the registering-wheel, whereby upon operating any one of said keys its corresponding tablet is exposed to view and its value registered on said registering-wheel, substantially as described.

16. In a cash register and indicator, the combination of a series of horizontally-reciprocating keys of fixed values, a series of vertically-reciprocating tablet-rods operated thereby and provided with projections and carrying indicating-tablets, a supporting-wing, a registering-wheel provided with a ratchet, a horizontally-vibrating bar extending transversely across said keys, a resetting-

spring for said bar, a series of projections on said keys at varying distances from said bar and arranged to engage therewith, a vibrating pawl-carrier pivoted on the axis of the registering-wheel and connected to said bar, and a pawl carried by said carrier and engaging with the ratchet on the registering-wheel, whereby upon operating any key its value is registered on the registering-wheel and its corresponding tablet-rod is elevated and its tablet held exposed to view, substantially as described.

17. In a cash register and indicator, the combination of a series of horizontally-reciprocating keys of fixed values, a series of vertically-reciprocating tablet-rods carrying indicating-tablets, a series of bell-cranks actuated by said keys and engaging with said tablet-rods, a registering-wheel provided with a ratchet, a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, and a pawl carried by said carrier and engaging with the ratchet on the registering-wheel, whereby upon operating any key its corresponding tablet is exposed to view and its value registered on the registering-wheel, substantially as described.

18. In a cash register and indicator, the combination of a series of horizontally-reciprocating keys of fixed values, a series of bell-cranks pivoted on a horizontal shaft at the rear of the machine, with their vertical arms engaging with the rear ends of the keys, a series of vertically-reciprocating tablet-rods provided with projections and resting at their lower ends on the horizontal arms of said bell-cranks and carrying at their upper ends indicating-tablets, a supporting-wing, a registering-wheel provided with a ratchet, a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, and a pawl carried by said carrier and engaging with the ratchet on the registering-wheel, whereby upon operating any key its value is registered on the registering-wheel and its corresponding tablet-rod is elevated and its tablet held exposed to view, substantially as described.

19. In a cash register and indicator, the combination of a series of horizontally-reciprocating keys of fixed values, a series of tablet-rods and tablets operated thereby, a registering-wheel provided with a ratchet, a horizontally-vibrating bar arranged transversely across said keys, a resetting-spring for said bar, a series of projections on said keys at varying distances from said bar and arranged to engage therewith, a pawl actuated by said bar

and engaging with the ratchet on the registering-wheel, and a stop arranged to engage with said pawl to positively lock the registering-wheel at the completion of the stroke of said 5 pawl, substantially as described.

20. In a cash register and indicator, the combination of a series of horizontally-reciprocating keys of fixed values, a series of tablet-rods and tablets operated thereby, a registering-wheel provided with a ratchet, a horizontally-vibrating bar arranged transversely across said keys, a resetting-spring for said bar, a series of projections on said keys at varying distances from said bar and arranged to engage therewith, a vibrating pawl-carrier pivoted on the axis of the registering-wheel and connected to said bar, a pawl carried by said carrier and engaging with the ratchet on the registering-wheel, and a stop arranged to engage with said pawl to positively lock the registering-wheel at the completion of the stroke of said pawl, substantially as described.

21. In a cash register and indicator, the combination of a series of horizontal reciprocating keys of fixed values, a series of tablet-rods and indicating-tablets operated thereby, a registering-wheel provided with a ratchet, a horizontally-vibrating bar pivoted at one side of the keys and extending transversely across the same, a series of projections on said keys arranged to engage said bar and vibrate it to different degrees, a pawl actuated by said bar and engaging with the ratchet of the registering-wheel, a horizontal screw-shaft secured 35 to the axis of the registering-wheel and revolving therewith, a pointer on said shaft and engaging with the thread thereof, and a registering-bar along which said pointer travels, substantially as and for the purpose described.

40. 22. In a cash register and indicator, the combination of a series of horizontally-reciprocating keys of fixed values, a series of tablet-rods and tablets operated thereby, a registering-wheel provided with a ratchet, a horizontally-vibrating bar extending transversely across said keys, a resetting-spring for said bar, a series of projections on said keys at varying distances from said bar and arranged to engage therewith, a pawl actuated by said bar 45 and engaging with the ratchet on the registering-wheel, a horizontal screw-shaft secured to the axis of the registering-wheel and revolving therewith, a pointer on said shaft and engaging with the thread thereof, and a registering-bar along which said pointer travels, substantially as and for the purpose described.

55. 23. In a cash register and indicator, the combination of a series of horizontally-reciprocating keys of fixed values, a series of tablet-rods and tablets operated thereby, a registering-wheel provided with a ratchet, a horizontally-vibrating bar extending transversely across said keys, a resetting-spring for said bar, a series of projections on said keys at 60 varying distances from said bar and arranged to engage therewith, a vibrating pawl-carrier pivoted on the axis of the registering-wheel

and connected to said bar, a pawl carried by said carrier and engaging with the ratchet on the registering-wheel, a horizontal screw-shaft 70 secured to the axis of the registering-wheel and revolving therewith, a pointer on said shaft and engaging with the thread thereof, and a registering-bar along which said pointer travels, substantially as and for the purpose 75 described.

24. In a cash register and indicator, the combination of a series of horizontally-reciprocating keys of fixed values, a series of vertically-reciprocating tablet-rods carrying indicating-tablets, a series of bell-cranks actuated by said keys and engaging with said tablet-rods, a registering-wheel provided with a ratchet, a horizontally-vibrating bar extending transversely across said keys, a resetting-spring 80 for said bar, a series of projections on said keys at varying distances from said bar and arranged to engage therewith, a vibrating pawl-carrier pivoted on the axis of the registering-wheel and connected to said bar, a pawl 85 carried by said carrier and engaging with the ratchet on the registering-wheel, a horizontal screw-shaft secured to the axis of the registering-wheel and revolving therewith, a pointer on said shaft and engaging with the thread 90 thereof, and a registering-bar along which said pointer travels, substantially as and for the purpose described.

25. In a cash register and indicator, the combination of a series of horizontally-reciprocating keys of fixed values, a series of bell-cranks pivoted on a horizontal shaft at the rear of the machine, with their vertical arms engaging with the rear ends of the keys, a series of tablet-rods provided with projections and resting at their lower ends on the horizontal arms of said bell-cranks and carrying at their upper ends indicating-tablets, a supporting-wing, a registering-wheel provided with a ratchet, a horizontally-vibrating bar extending transversely across said keys, a resetting-spring for said bar, a series of projections on 100 said keys at varying distances from said bar and arranged to engage therewith, a vibrating pawl-carrier pivoted on the axis of the registering-wheel and connected to said bar, a pawl carried by said carrier and engaging with the ratchet on the registering-wheel, a horizontal screw-shaft secured to the axis of the registering-wheel and revolving therewith, a pointer on said shaft and engaging with the thread thereof, and a registering-bar along which said pointer travels, substantially as and for the purpose described.

26. In a cash register and indicator, the combination of a series of horizontally-reciprocating keys of fixed values, a series of bell-cranks pivoted on a horizontal shaft at the rear of the machine, with their vertical arms engaging with the rear ends of the keys, a series of tablet-rods provided with projections and resting at their lower ends on the horizontal arms of said bell-cranks and carrying at their upper ends indicating-tablets, a sup- 105 110 115 120 125 130

porting-wing, a registering-wheel provided with a ratchet, a horizontally-vibrating bar extending transversely across said keys, a resetting-spring for said bar, a series of projections on said keys at varying distances from said bar and arranged to engage therewith, a vibrating pawl-carrier pivoted on the axis of the registering-wheel and connected to said bar, a pawl carried by said carrier and engaging with the ratchet on the registering-wheel, a stop arranged to engage with said pawl to positively lock the registering-wheel at the completion of the stroke of said pawl, a horizontal screw-shaft secured to the axis of the registering-wheel and revolving therewith, a pointer on said shaft and engaging with the thread thereof, a registering-bar along which said pointer travels, a second horizontally-vibrating bar extending transversely across the keys, a resetting-spring for said bar, a second series of projections on said keys arranged to engage with said bar, a gong, and a gong-hammer actuated by said bar, substantially as and for the purpose described.

27. In a cash register and indicator, the combination, with a series of horizontally-reciprocating keys of fixed values and a registering-wheel provided with a ratchet, of a horizontally-vibrating bar pivoted at one side of the keys and extending transversely across the same, a series of projections on said keys arranged to engage said bar and vibrate the same to different degrees, and a pawl actuated by said bar and engaging with the ratchet of the registering-wheel, whereby upon operating any one of said keys its value is registered on said registering-wheel, substantially as described.

28. In a cash register and indicator, the combination, with a series of horizontally-reciprocating keys of fixed values and a registering-wheel provided with a ratchet, of a horizontally-vibrating bar pivoted at one side of the keys and extending transversely across

the same, a series of projections on said keys arranged to engage said bar and actuate it to different degrees, a vibrating pawl-carrier pivoted on the axis of the registering-wheel and actuated by said vibrating bar, and a pawl carried by said pawl-carrier and engaging with the ratchet of said wheel, whereby upon operating any one of said keys its value is registered on said registering-wheel, substantially as described.

29. In a cash register and indicator, the combination of a series of horizontally-reciprocating keys of fixed values, a series of tablet-rods and indicating-tablets operated thereby, a registering-wheel provided with a ratchet, a horizontally-vibrating bar extending transversely across said keys, a series of projections on said keys arranged to engage said bar and vibrate the same to different degrees, and a pawl actuated by said bar and engaging with the ratchet of the registering-wheel, whereby upon operating any one of said keys its indicating-tablet is exposed to view and its value is registered on said registering-wheel, substantially as described.

30. In a cash register and indicator, the combination of a series of horizontally-reciprocating keys of fixed values, a series of tablet-rods and indicating-tablets operated thereby, a registering-wheel provided with a ratchet, a horizontally-vibrating bar pivoted at one side of said keys and extending transversely across the same, a series of projections on said keys arranged to engage said bar and vibrate it to different degrees, a vibrating pawl-carrier pivoted on the axis of the registering-wheel and actuated by said vibrating bar, and a pawl carried by said carrier and engaging with the ratchet of the registering-wheel, substantially as and for the purpose described.

MANFRED U. LOREE.
